UNITED STATES PATENT OFFICE.

CHARLES F. MARTINE, OF BOSTON, MASSACHUSETTS.

IMPROVEMENT IN TUCK-CREASING MECHANISM FOR SEWING-MACHINES.

Specification forming part of Letters Patent No. **104,612**, dated June 21, 1870; antedated June 9, 1870.

To whom it may concern:

Be it known that I, CHARLES F. MARTINE, of Boston, county of Suffolk, and State of Massachusetts, have invented an Improved Tuck-Marker for Sewing-Machines; and I do hereby declare the following to be a full, clear, and exact description thereof, reference being had to the accompanying drawing, in which—

Figure 1 represents a sewing-machine with my improvements attached. Figs. 2 and 3 are detailed views.

The object of my invention is to produce a tuck-marker which can be attached readily to a sewing-machine, and which will efficiently do the work required, while it will be not only cheap in construction, but durable; and the nature of my invention consists in an elastic cushion, so constructed as to be easily adjusted to the needle-bar of a sewing-machine; and a marker or creaser, upon which the elastic cushion presses with the action of the needle-bar; and a gage, in combination with the creasing device; and a device for adjusting the height of the creases.

In the drawing, A B represent a sewing-machine, for example. D is the needle-bar. C is an elastic cushion. It may be of rubber, leather, springs, or any elastic construction. It is held in a clamp, E, which extends beyond the cushion, forming the socket H. This socket is the means by which the cushion is attached to the needle-bar.

G is a gage, and is part of plate K. The rod S, one end of which is bent and flattened to form the creaser L, is adjustable by means of clamps *a a* and thumb-screw *m*, which also serves to regulate the gage G.

P is a device for raising or lowering the creaser L, and is adjusted to the shank of L,

so that it can be moved under L, and thus raise or lower the creaser. This is desirable when the elastic cushion does not come down upon the creaser with sufficient force. The rod S being round and turning with ease in clamps *a a*, readily admits of this raising and lowering of the creaser L.

The elastic cushion presents the great advantage over metallic marking devices in that it bears directly upon the edge of creaser L, and the elasticity allows the cushion to press upon each side of the creaser L, thus giving a sharper crease in the cloth than can be made when the parts are all metal, as in the tuck-markers generally in use.

The operation of my tucker is very simple, and is readily understood from the description of the parts given above.

I am aware that there is no particular novelty in the gage G, nor do I claim any; but,

Having fully described my invention, what I claim as new, and desire to secure by Letters Patent, is—

1. The combination, with the creasing-edge L, of the elastic cushion C, socket E, and needle-bar D, when arranged as and for the purpose described.

2. The combination of elastic cushion C, needle-bar D, creaser L, gage G, plate K, clamps *a a*, and the plate of a sewing-machine, all constructed, arranged, and operating substantially in the manner herein described.

In testimony whereof I have signed my name to this specification in the presence of two subscribing witnesses.

CHAS. F. MARTINE.
